W. SCHMID

CHOKE VALVE MECHANISM

Filed June 18, 1926

Inventor:
William Schmid
By G. A. Gross Atty.

UNITED STATES PATENT OFFICE.

WILLIAM SCHMID, OF COLDWATER, MICHIGAN, ASSIGNOR TO HARRY A. DOUGLAS, OF BRONSON, MICHIGAN.

CHOKE-VALVE MECHANISM.

Application filed June 18, 1926. Serial No. 116,861.

My invention relates to the choke valves that are employed in connection with internal combustion hydrocarbon engines of automobiles for the purpose of admitting liquid 5 gasoline into the engines, in starting.

Hitherto, these choke valves have been equipped with operating push and pull rods moved longitudinally by means of sliding handles which are pulled upon when the 10 liquid gasoline is to be admitted to the engines and which are pushed upon when the flow of such gasoline is to be cut off.

It is the object of my present invention to provide a handle which may be turned 15 to secure the valve adjusting movements of the push and pull rod connected with a choke valve. In carrying out my invention, mechanism is employed having one portion connected with the handle to be turned by 20 the hand and another portion reciprocable by the first and connected with the rod to move it longitudinally to secure the desired adjustments of the valve. These two portions of the mechanism which serve to convert 25 the turning movement of the handle into reciprocable movement of the rod are desirably in cam engagement, the portion of this mechanism which is connected with the rod being provided with a guide whereby 30 this mechanism portion is restricted to straight line reciprocable movement as the complementary portion of said mechanism is turned.

The invention will be more fully explained 35 in connection with the accompanying drawing in which Fig. 1 is a front view illustrating the handle of the device of my invention as it is assembled with a dash board; Fig. 2 is a side view of the device of my 40 invention in association with piping which serves to convey liquid gasoline to an engine; Fig. 3 is a side view, on a larger scale, illustrating the cam mechanism of my invention in conjunction with the turning handle and the adjacent end of the push and 45 pull rod; Fig. 4 is a sectional view on line 4—4 of Fig. 5; and Fig. 5 is a sectional view substantially on line 5—5 of Fig. 3.

The choke valve 1 is disposed within air 50 inlet piping 2 that leads to a carburetor 3 and from which carburetor piping 3' leads to the engine intake manifold. This choke valve is operated by a push and pull rod 4 which is connected at its forward and lower 55 end with the valve and at its rear and upper

end with an operating member 5. When the rod 4 is pulled upon the choke valve is moved in a closing direction to reduce the amount of air being carbureted and to increase the amount of liquid gasoline that is admitted 60 to the engine, in starting, all as is well understood. In the preferred embodiment of the invention, the operating member 5 is formed of a spring rod folded at its mid portion to form a T-shaped structure whose 65 stem is formed in two slightly diverging parts 6 and whose head passes through slots 7 in a cylindrical shell 8, these slots desirably being in one plane that includes the axis of the shell. The ends of the T-shaped 70 structure 5 are desirably provided with washers 9 that are held in place by pins 10, the shell 8 being between these washers and so engaging the shell as to spread the portions of the T-stem apart against the resilience 75 of the rod forming this stem, an arrangement that eliminates looseness of the assembly of the T-shaped member 5 with the shell 8 to avoid noise. The push and pull rod 4 is desirably upwardly turned, as 80 indicated at 11, and passes through an opening formed at the right of the rod that forms the T-shaped member 5, a pin 12 passing through the portion at 11 above the member 5 to hold the parts 4 and 5 in assembly. 85 The shell 8 is secured to a mounting plate 13 and this mounting plate is secured to the dash board 14 by means of bolts 15. A handle 16 has a hub portion 17 which is journaled in the mounting plate 13. Another 90 shell 18 is fixed upon the inner end of said hub 17 and is enclosed by the shell 8. The shell 18 has oblique slots 19 through which the ends of the head of the T-shaped member 5 are passed. As the handle is turned, 95 the head of the member 5 moves along the inclined slots 19 and within the straight slots 7, the two sets of slots cooperating to cause straight line movement of the T-shaped member 5 to push or pull the rod 4 according 100 to the direction of turning movement of the handle. Referring to Fig. 1, when the handle is pointed to the index line marked "Start," the choke valve 1 is closed and when it is pointed to the index line marked "Run," 105 the choke valve is open. Springs 20 are interposed between the mounting plate 13 and the shell 18 to hold the handle hub flange 21 snugly against the mounting plate. The springs 20, which are preferably struck from 110

the shell 18, thus serve to eliminate noise at the handle and the parts located at and carried by the handle.

Changes may be made without departing from the invention.

Having thus described my invention, I claim:

1. The combination with a choke valve for an internal combustion engine; of a push and pull rod connected with the valve to operate it; a handle mounted to turn; a shell secured to and coaxial with the handle and formed with opposite inclined cam slots; an operating member connected with said rod and in the form of a T constructed of a rod folded at its mid portion to form a stem; a second shell having guiding slots, the ends of the head of the T-shaped operating member being received in the slots

in both shells, these head ends carrying portions which engage the outer side of the second shell and which serve to exert spreading action upon the stem of the T-shaped operating member.

2. The combination with a choke valve for an internal combustion engine; of a push and pull rod connected with the valve to operate it; a handle mounted to turn; a shell secured to and coaxial with the handle and formed with an inclined cam slot; an operating member connected with said rod and engaged in said cam slot; a mounting plate for the handle; and a spring interposed between said mounting plate and shell.

In witness whereof, I hereunto subscribe my name.

WILLIAM SCHMID.
